(57) **CLAIM**

We claim the ornamental design for a hand held remote, as shown and described.

DESCRIPTION

FIG. 1 is a first perspective view showing primarily the front, right side and bottom;

FIG. 2 is a second perspective view showing primarily the back, left side and top;

FIG. 3 is a front view;

FIG. 4 is a back view;

FIG. 5 is a side view, with the left side and right side being mirror images of each other;

FIG. 6 is a top view; and,

FIG. 7 is a bottom view.

The broken lines in FIGS. 1, 3 and 5-7 depict portions of the hand held remote that are not part of the claimed design.

1 Claim, 6 Drawing Sheets(56)
